VENETIAN BLIND

Filed March 3, 1949

UNITED STATES PATENT OFFICE

2,579,137

VENETIAN BLIND

Rudy Bruner, New York, N. Y.

Application March 3, 1949, Serial No. 79,339

1 Claim. (Cl. 160—173)

1

This invention relates to Venetian blinds and more particularly to tilt rail and bottom rail construction and their association with the tapes and cords of such devices.

An object of this invention is to provide a novel and improved construction in hollow-type tilt rails made of parts reasonably cheap to manufacture, easy to assemble and affording secure attachment in a very simple manner of the tapes as well as guiding and anchoring means for the cords; features of such construction being also adaptable for hollow-type bottom rails in Venetian blind assemblies.

Another object hereof is to provide novel and improved tilt and bottom rail constructions, which are of sheet metal or the like, and which require no screws, bolts, staples or similar means for attachment of the tapes and cords thereto, which include brackets and casings of novel and improved design and function, associated in novel and improved manner so that the device is efficient in carrying out the purposes for which it is intended.

Other objects and advantages will become apparent as this disclosure proceeds.

In the accompanying drawings forming part of this specification, similar characters of reference indicate corresponding parts in all the views.

Fig. 1 is a front view of a Venetian blind embodying the teachings of this invention.

Fig. 2 is a fragmentary perspective view showing channel and cover construction to be cut in proper lengths for use as tilt rails, and bottom rails if desired, in Venetian blind assemblies as for instance shown in Fig. 1.

Fig. 3 is an "exploded" perspective view. A bracket I have devised, one of which is mounted at each station of the tapes, within the casing member illustrated in Fig. 2, is adapted to anchor the ends of an associated pair of tapes and provide a guiding means for one of the cords used to bunch the slats. The manner of forming the ends of the tapes is also shown, so that it may be received onto mounting fingers included in the bracket structure.

Fig. 4 is a section taken at line 4—4 in Fig. 1, showing the manner of assembly of bracket and casing, the manner of attachment of the tapes which are led out of the casing through slots, or else, if desired said tapes may be led out of the casing as shown in Fig. 5.

Fig. 5 is a section taken at line 5—5, showing use of the bracket shown in Fig. 3 within the bottom rail; said bracket being here minus its cord-guiding pulley, as such pulley is here unnecessary. The tapes as here shown, and of course adaptable in Fig. 4, are led out of the channel before the casing cover slat is inserted in place.

In the drawings, the numeral 15 designates

2

generally a Venetian blind, whose tilt rail is denoted by the numeral 16, its bottom rail by 17, and the slats intermediate such rails by 18. Said rails are hollow casings made of sheet metal or other suitable sheet material. Each casing comprises a channel member 19 and its associated slat 20 to form a tubular structure, whose ends may be closed by cap members 16' and 17'. The cap members 16' at the ends of the tilt rail 16, may each have suitable pintles for mounting in end brackets 21 and 22, at opposite sides of the window frame 23. Tilter means, not shown, may be housed in bracket 21, and operated by the cords 24. Lock for the cords may be housed within the tilt rail 16, and especially a bracket 25 at each pair of tapes, is mounted within the tilt rail. The cord lock is not shown, and likewise the cord system, which are well known in the art, and need no further explanation. The slats 18 may be of sheet metal and their stock may be used for the cover slat 20. Their material has some resilience usually, and are transversely archable. In Venetian blind assemblies, two tapes facing each other with the slats 18 between them, and a cord through all the slats 18, and positioned parallel to the tapes, are at several stations across the Venetian blind 15, as is well known.

The feature of this invention is the manner and means of attachment of the tapes and cords and of the provision of pulley guides or their equivalent at the regions of tape attachment, and the association of said means with the tilt and bottom rails, all of which I will now describe.

The base of the channel 19 is preferably outwardly transversely arched slightly, so that the sides of the channel may be sprung. The channel sides are so formed that each has a pair of spaced channels along its entire length, preferably along the base of the channel 19 and along the longitudinal free edge of the walls respectively. The channels 30 and 31 in one of the walls being directly opposite the channels 30' and 31', respectively in the other of the walls of channel 19; all channels in said walls, opening inwardly in the channel member 19. At each position of a pair of tapes, the base of channel 19 is provided with a hole 32. At each such position, within the channel 19, is mounted a bracket 25, which may be a stamping out of a single blank of sheet metal.

The base of bracket 25 has a pair of opposite edges 26 and 26', which are of such distance apart that such edges may be fitted to lie respectively within the respective channels 30 and 30'. From that surface of the base of bracket 25, which is next to the base of channel 19, extends a nipple 33. This nipple sets within hole 32 in channel 19, and locks the bracket 25 in proper position within the channel 29. From the

opposite surface of the base of said bracket 25, meaning the surface exposed when the bracket is mounted within the channel 19, there extends adjacent each of the sides of the channel 19, bent up parts 34 and 35, to form a loop having an entrance at 36 between such parts 34 and 35, so that the hemmed end 37 of tape 38 may be mounted on such loop parts 34 and 35, one such tape on each pair of such parts 34 and 35. Such hem is first received about part 34, and then let spread so that part 35 also enters the hem. The tape end is thus anchored.

For better identification, the tapes at the front of the Venetian blind 15, are designated by the numeral 38, while the tapes at the back thereof, are designated by the numeral 38''. Also the parts 34 and 35 to receive the rear tape, are indicated as primed.

At tape positions on the tilt rail 16, where there is also a cord for the movement of the bottom rail 17, said bracket 25 which is used at such position, is provided with a cord-guiding means as for instance the pulley 40 to receive such cord which is positioned through the nipple 33. Tabs 41, bent up from the blank out of which the bracket is made, serve as supports for the pin shaft 42, carrying the pulley 40.

In the bottom rail, the casing used for the tilt rail 16 is used in inverted position as the bottom rail 17 shown in Fig. 5. Here the cord 39 is anchored by a knot 43 at its end, after passing through nipple 33' of bracket 25'. This bracket 25' is the same as shown in Fig. 3, but has no pulley for none is needed.

Two different ways are shown of the manner in which the tapes enter the rail casing. In Fig. 4, the tapes are shown entering the casing through the slots 44 and 44' respectively. In Fig. 5, said tapes are held gripped between the channel member 19' and its cover slat 20'. Either method of tape entrance into the rail casing is useable for the tilt and bottom rail assemblies.

The parts 34 and 35, and likewise the opposite set of parts 34' and 35', constituting the split loops for attachment of the tapes, are spaced from the walls of the channel 19, to facilitate accessibility for mounting and removing the tapes. If parts 35 and 35' are omitted, then parts 34 and 34' may serve as hooks to receive the hemmed ends of the tapes, respectively.

This invention is capable of numerous forms

and various applications without departing from the essential features herein disclosed. It is therefore intended and desired that the embodiment herein described be deemed illustrative and not restrictive and that the patent shall cover all patentable novelty herein set forth; reference being had to the following claim rather than to the specific description herein to indicate the scope of this invention.

I claim:

A bracket for mounting a pair of opposite tapes of a Venetian blind including a channel rail having a hole through its base wall and opposite channels, one such channel along each of its side walls at the base wall, said bracket being of a single piece of sheet metal and comprising a base having an open-ended nipple extending from one surface of said base and presenting at its other surface a pair of spaced parallel hooks bent up from the base; each hook being adapted to receive a hemmed end of a tape thereon; said bracket being adapted to be slid within the channel rail whereby opposite longitudinal edges of the base of the bracket are respectively positioned in the opposite channels along the walls of the channel member and is locked in position when said nipple enters and becomes removably engaged in the hole in the base wall of the channel member; each of said hooks lying along one of said edges of the base member and respectively spaced from the side wall of the channel member when the bracket is so mounted within the channel member.
